UNITED STATES PATENT OFFICE.

HARRY W. COLBY, OF CHICAGO, ILLINOIS, ASSIGNOR TO THOMAS F. KEELEY, OF CHICAGO, ILLINOIS.

MACHINE FOR APPLYING COVERINGS TO MEATS.

Application filed May 23, 1924. Serial No. 715,836.

My invention is particularly adapted and intended for applying elastic jackets to joint meats, such as hams, shoulders and the like, and hereinafter is more particularly described with reference thereto. However, it is also adapted with obvious modifications to apply flexible coverings to a great variety of other articles. When used for the purpose of covering hams and similar joint meats, the jackets may be applied either before or after the meats have been smoked and the jackets may be of elastic material such as stockinette, or relatively inelastic material such as muslin. The machine is especially useful, however, in applying jackets of stockinette or the like to the joints prior to smoking, in accordance with the patent to Fitzgerald No. 1,122,715. According to the process of this said patent, the hams or other joints after being pickled and before further treatment, are encased in close fitting bags made of elastic fabric, such as stockinette, and then smoked in substantially the usual manner, after which they are ready for the market without further handling. The jacket is preferably prepared as a bag or sleeve, having one end closed and the other open, and after the ham is inserted, the open end is closed by sewing, knotting, or otherwise. My machine is particularly designed for applying jackets of this character. By the use of my machine a great saving is effected in the time and labor required to encase the hams in their jackets, the latter are evenly applied to the joints so that after the jacket is closed and in the smoking operation even pressure is brought to bear upon the softer parts of the meat by reason of which the finished joint is compact and rounded and presents an attractive and merchantable appearance.

The form of the invention hereinafter described comprises a pair of guides for the joint over the ends of which the open jacket is stretched and a power operated plunger by which the joint is pushed between the guides and into the bag or jacket. The guides are pivoted at their rear ends and converge or approach each other toward the bag holding ends thereof. As the joint is driven forward the guides swing outward away from each other under the pressure of the ham, distending the jacket so that the ham may readily enter the same, irrespective of its size, and

the movement of the guides actuates a counter or counters so that tally is kept of the number of joints jacketed. Other features and advantages of the present invention will appear from the following detailed description thereof. It is to be understood, however, that the specific disclosure is for the purpose of exemplification only and that the scope of the invention is defined in the following claims in which I have endeavored to cover it as broadly as possible in view of the prior art as known to me.

In the drawings accompanying and forming a part of the specification, Fig. 1 is an isometric view of a preferred embodiment of my invention; Fig. 2, a front elevation thereof; Fig. 3, a plan partly in horizontal section on the line 3—3 of Fig. 4; Fig. 4, a vertical transverse section on the line 4—4 of Fig. 3; Fig. 5, a transverse vertical section on the plane of the line 5—5 of Fig. 3; Fig. 6, a horizontal plan partly in section on the line 6—6 of Fig. 4; Fig. 7, a vertical longitudinal section of a detail, partly broken away and partly in elevation; Fig. 8, a transverse vertical section of another detail; and Fig. 9 is a cross-section on the line 9—9 of Fig. 3.

Each part is identified by the same reference character wherever it occurs in the several views.

The mechanism of my invention may be mounted in any suitable manner and I have shown it as supported upon a table or stand 11, the specific construction of which it is unnecessary to describe. The swinging guides for the meat to be packaged are shown at 12, 13, the plunger for forcing the joints forwardly between the guides at 14, and the counters to which reference has been made, at 15, 16.

The swinging guides 12, 13, are of similar construction and shape, comprising each an elongated interiorly convex portion 17, which, at its forward or free end, is formed with an upwardly extending wing 18, the two wings on the respective guides substantially coming together when the guides are in normal closed position, as best shown in Fig. 2. As shown in Figs. 1 and 3, the nozzle formed by the guides extends beyond the front edge 19 of the table, so that the wings 18 are clear thereof and the table is provided with a bottom guide or exten-

10 sion 20, the upper surface of which is substantially flat and may be tapered and of rounded form at its end, as best shown in Fig. 3. The side edges of the bottom guide 20 are formed with downwardly projecting flanges or ribs 21 (see Fig. 9) to hold the lower edge of a bag on the guides well away from the top surface of the lower guide. In using the machine, the bag or container is slipped over the nozzle formed by guides 12, 13 and 20 preferably until its forward edge or mouth is at or beyond the rear edges 22 of the wings 18, so that the operator may readily hold the bag in position while the hand or other joint is being slipped into it. The rear ends of the respective swinging guides are formed or provided with sleeves 23, which receive the stationary pivot pins 24, thus providing for the swinging movement of the said guides. The sleeves 23 of the swinging guides are formed or provided with rearwardly extending arms 26, 27 from which extend inwardly and into the path of the plunger 14, arms 28, 29. As the plunger returns to normal position it engages said inwardly extending arms, forcing them rearwardly, and thus closes the swinging guides. The inner ends of arms 28, 29 are connected by links 30, 31 to a central sliding guide 32. The latter slides in a sleeve 33 of a bracket 34 bolted to the table at the middle thereof. In the preferred construction shown, the guide 32 is formed with a flattened head and the links 30, 31, are pivoted on a pin 35 extending through said flattened head, the link 31 being above and the link 32 below the same. The inner ends of links 30, 31, are faced off at an acute angle to the length thereof, which angle is similar in the two links so that when the swinging guides are in their closed or normal position, as shown in full lines in Fig. 3 and in Fig. 6, and consequently the bolt 32 is in its rearmost position, the ends of the links 40 rest against the flat front face 37 of the guide 33, and therefore the guides 12, 13, are accurately positioned over the guide 20 in their closed position with their meeting edges directly over the center line of said guide 20. By reason of the construction just described, the swinging guides are always moved an equal distance from the median line of the machine so that the jacket on the nozzle formed by the swinging guides and the stationary guide beneath them and the joint as it is inserted therein are always in proper position and symmetrically placed with reference to the machine.

45 In the preferred form of the invention herein described, the plunger 14 by which the meat joints are pressed or moved through the nozzle formed by the guides and into the jacket, is operated by a pneumatic cylinder, though obviously other means might be employed for the purpose. The cylinder

38 of the pneumatic motor is supported in a bracket 39 on the top of the table or stand and it may be of any suitable or usual construction. In the form shown it is provided with an air pipe 40 leading to the rear end thereof, and an air pipe 41 communicating with the front end of the cylinder through a casting 42 which closes the front end of the cylinder. The piston of the motor is shown at 43 and the rod 44 thereof extends through the packing box 45 at the front end of the cylinder and carries the plunger 14. As heretofore stated, the piston rod 44 is guided in the bracket 31 which is formed with an opening for this purpose. A compressed air supply for operating the motor may be controlled by any usual or approved valve system, and I have shown the supply pipes 40, 41 connected to a rotary valve 47 located conveniently at the front end of the machine for this purpose. Valve 47 is provided with an inlet port 48 connected by pipe 49, 50, with a suitable source of compressed air and an exhaust port 51. By rotating the valve plug the supply of air and exhaust can be alternately connected to the respective ends of the motor cylinder. It is convenient to operate the valve plug by means of a pedal or pedals, leaving the hands of the operator or operators free to handle the jackets and joints. For this purpose I have provided the valve plug with an operating arm 53 and a pair of pedals 54, 55, arranged on opposite sides of the front of the machine and connected to the arm 53 so that the machine may be operated from either side, and if desired, by a pair of operatives working it alternately. The pedals 54, 55, are pivoted in brackets 56, 57, and the inner arms 58, 59 of the pedals, which are slightly off-set with respect to each other, are pivoted to the respective links 60, 61, the upper ends of which are pivoted to arm 53 at 62.

55 A spring 63 serves to return the valve plug and pedals to normal position after each operation. Normally, the piston and plunger are in the rear position shown in Figs. 1 and 3, the air supply being in communication with the front end of the cylinder. When either of the pedals 54, 55 is lowered the valve is turned to open the front end of the cylinder to exhaust and connect the rear end thereof to the supply of compressed air whereby the piston and plunger are driven forward. On its return stroke the plunger or follower engages the arms 28, 29, connected to the swinging guides, thereby closing guides 12, 13, and it is to be observed, by reference to Fig. 3, that when the plunger is in its normal, rearmost position, the rear face thereof is in contact with said arms and until the plunger moves forward therefor the guides are locked in their inner or closed position shown in Figs. 1 and 3. Thus,

accidental registration upon the counters, to which reference has been made, by movement of the swinging guides, is prevented.

The counters 15, 16, at the rear of the machine, are operated from the arm 26 attached to swinging guide 20. To the rear end of said arm is bolted an inwardly extending bracket 64, the free end of which is perforated for the reception of a pivot pin 65. Said pin extends through the inner end of a link 66, the outer end of which is pivoted to a lever 67, the lower end of the pivot 67 resting and sliding upon the table. The forward end of lever 67 is pivoted to the table at 68 and the rear end drives the bar, to be presently described, by which the counters 15, 16, are actuated. It will be observed that the distance between the fulcrum 68 of lever 67 and the point of attachment of link 66 is very materially less than the length of the arm 26 between the pivotal point of the latter and the point of attachment thereto of link 66. As a consequence, the lever 67 moves through a considerably greater angle than arm 26, which is necessary or useful to secure the proper extent of movement of the slide which operates the counting mechanism.

The counter operating slide 70 extends transversely of the machine and is supported in guides 71, 72 at the rear end thereof. Guide 72 is provided with an anti-friction roller 73 against which the upper face of the bar 70 bears at one end (see Fig. 5). The bracket 71 which supports the other end of the slide is formed with an open top bearing 74, through which the slide bar works. Slide bar 70 is connected to the lever 67 previously described by a link 75. The eye or perforated boss 76 of the link slips over the pivot pin 77 on the slide, and the inner end of the link is formed with a socket which receives the pin 78 projecting from the lower face of the lever 67. By reason of this construction, the slide bar cannot be disconnected from the lever without raising the latter. The lever 67 is held down upon the table top at its rear end by a transverse guide 79, which extends over said lever and partially across the top of the table.

As the construction connecting the swinging ends of the arms 28, 29 extends beneath the rod connecting the piston and plunger or follower and because of the construction just described, the machine cannot be disassociated or disassembled without removing the pivot pins 24. The latter are locked in place by a transverse rod 80 extending through the same and beneath the table top. As a consequence of the foregoing, the means for actuating the counters cannot be readily so disconnected from the main operating elements of the machine that the latter can be used for jacketing joints without registering on the counters.

If it is desired only to count all of the pieces of meat jacketed in the machine, a single counter 15 may be employed.

If, however, it is desired to keep count separately of the large pieces, such as hams, and the smaller pieces, such as shoulders, or picnic hams, the two counters 15, 16 shown may be employed. The counters are or may be of a kind commonly found on the market for registering the revolutions of rotating machinery. Such counters are ordinarily formed with a swinging arm which projects into the path of a cam surface on a rotating part. For the present purpose I have somewhat modified the form of the arms of the counters to better adapt them for cooperation with the actuating slide 70, so that a shorter movement of said slide will serve to actuate the counters. The arms 81, 82, of the counters are bent at an angle as at 83, 84, and the counters secured to the table in such position that the innermost portions of the bent arms are approximately perpendicular to the path of movement of the slide. The slide is preferably formed with a pair of openings 85, 86, through which the arms 83, 84 respectively, extend, the edges of the respective slots or openings being rounded at 87, 88, where they engage the respective arms of the counters. The reciprocation of the slide from the left to the right, as shown in Fig. 5, when of sufficient extent, operates the counters. It is to be observed, however, that the slot 86 through which the arm of counter 16 extends is of greater length than the slot 85 through which the arm of counter 15 extends and that in the normal position of the parts shown in Fig. 5 the operating edge 87 of slot 85 is close to arm 83 of counter 15, whereas the operating edge 88 of slot 86 is spaced a considerable distance from arm 82. A relatively short movement of the slide therefore is sufficient to operate counter 15, but a much greater movement is essential to operate counter 16. The extent of movement of the slide, which is, as above pointed out, operated by the swinging guides depends on the size of the joint being jacketed, and the slots in the counter actuating bar and the cooperating parts are so designed that both counters are operated by hams of ordinary size and only counter 15 by picnic hams or shoulders. It is therefore possible to keep tally of both the entire number of hams and of the respective kinds of joints. Preferably a housing 90 is attached to the counter actuating bar over arms 81, 82 to prevent tampering therewith.

As previously described accidental actuation of the counters is practically impossible and the use of the machine for jacketing hams without registration on the counters can only be accomplished by a rather diffi-

cult mechanical operation which would expose anyone attempting it to detection. Thus the machine provides a reasonably certain means of keeping count of the meat 5 jacketed as well as a labor and time saving means for applying the jackets.

I claim:

1. In a machine of the class described, a pair of pivoted guides mounted to swing in 10 a horizontal plane, a stationary guide beneath said swinging guides, said stationary guide being formed with longitudinal ribs on its undersurface, and a plunger movable between the swinging guides.
2. In a machine of the class described, a support, a pair of swinging guides pivoted to said support at their rear ends, a stationary horizontal guide extending beyond said support and adapted to receive the mouth 15 of a bag thereover beneath said swinging guides and substantially on a level with said support and a plunger movable over the support between the swinging guides.
3. In a machine of the class described, a support, a pair of horizontal guides pivoted on said support, a plunger movable between said swinging guides and inwardly extending arms on said guides adapted to be engaged by the plunger to swing said guides 20 together.
4. In a machine of the class described, a support, a pair of horizontally swinging guides mounted on said support, a plunger movable between said guides, inwardly projecting arms rigidly connected to the respective swinging guides and means so connecting the arms that the latter move equal distances from a central line.
5. In a machine of the class described, a support, a pair of swinging guides mounted thereon and movable in opposite directions 25 thereover, arms rigidly connected to the respective guides and extending toward each other, a sliding member movable in a line intermediate said guides, links connecting the slide and said arms and a plunger moving longitudinally between said guides and adapted to engage said arms to return the guides to closed position.
6. In a machine of the class described, a support, a pair of normally converging oppositely movable guides pivoted at their front ends on the support and adapted to swing apart, a plunger movable on a longitudinal line intermediate said guides and power operated means for reciprocating the plunger.
7. In a machine of the class described, a table, a pair of swinging guides pivoted thereon for horizontal movement thereover, arms connected to said guides and extending toward each other, a slide movable longitudinally between said guides, links connecting said slide and arms, a plunger movable 50 longitudinally between said guides and

adapted to engage said arms to close said guides and a power operated means for moving said plunger.

8. In a machine of the class described, a support, a pair of converging guides mounted on the support, one of said guides being pivoted to the support for lateral movement thereover, a bottom guide extending beyond said support and adapted to receive the mouth of a bag thereover and a plunger 75 movable longitudinally between said guides.

9. In a machine of the class described, a support, a pair of converging guides mounted thereon, one of said guides being pivoted thereto for lateral movement thereover, a plunger longitudinally movable between said guides, a counter and means intermediate the movable guides and said counter for operating the latter.

10. In a machine of the class described, a support, a pair of converging guides mounted thereon, one of said guides being pivoted thereto for lateral movement thereover, a counter, a bar movable transversely of the machine for operating the counter, a lever connected to the bar and movable guide for operating said bar, and a plunger movable longitudinally intermediate said guides.

11. In a machine of the class described, a support, a pair of converging guides mounted on the support, one of said guides being pivoted for lateral movement over the support, a plunger movable longitudinally between said guides, a lever operated by the movable guide, a transversely sliding bar operated by said lever and a counter, the operating element of which is arranged to be moved by said bar.

12. In a machine of the class described, a support, a pair of converging guides mounted on the support, one of the same being pivoted thereto for movement laterally thereover, a lever connected to the movable guide to be swung thereby, a pair of counters and connections intermediate said counters and said lever whereby one of said counters is moved by a relatively small movement of said lever and the other of said counters is moved only by a substantially greater movement of said lever.

13. In a machine of the class described, a support, a pair of converging guides mounted thereon, a plunger movable longitudinally intermediate of said guides, a pair of counters having operating arms projecting therefrom, a sliding bar having abutments thereon for engaging the arms of the counters, said abutments being so spaced relative to the arms of the counters that one of said arms is engaged and operated by the bar substantially before the other, and connections intermediate the bar and the movable guide whereby the movement of the guide reciprocates said bar.

14. In a machine of the class described, a

support, a pair of converging guides on said support, one of said guides being pivoted thereto for lateral movement thereover, a plunger longitudinally movable intermediate said guides, an arm on the movable guide projecting rearwardly therefrom, a lever pivoted to said support, a link connecting

10
said arm and lever for operating the latter, a transversely moving slide, a link connecting said slide and lever, and a counter having an arm projecting into the path of said bar and adapted to be operated thereby.

HARRY W. COLBY.
